MOTOR DRIVEN WHEEL CHAIR

Homer P. Smith, Seattle, Wash.

Application October 17, 1938, Serial No. 235,437

4 Claims. (Cl. 180—29)

This invention relates to motor driven wheel chairs and an object of this invention is to provide a motor driven wheel chair that can be moved forwardly or rearwardly at will and that can be turned in either direction either on the vertical axis of the chair or on the vertical axis of either of the wheels and that can be moved in substantially any manner desirable to the occupant.

10 Another object of the invention is to provide efficient control means for an electrically driven wheel chair whereby the occupant can control all of the movements of the chair by a simple process of closing electric switches.

15 Another object is to provide control means of this nature that is particularly well adapted to be operated by invalids, said control means comprising switches that are easily operated but that must be held closed by conscious effort on the 20 part of the operator and that will move to open position in case the operator loses consciousness.

Another object of the invention is to provide a wheel chair which is compact in construction and relatively short in over all length whereby it 25 may be turned in a small space.

Another object is to provide a motor driven wheel chair having four independently controlled driving shafts, two of which are connected with each wheel of the chair for selectively driving 30 either of said wheels or both of said wheels in either desired direction whereby said chair may be moved forward or backward or may be turned in either direction either on the vertical axis of the chair or on the vertical axis of one of the 35 wheels.

Another object is to provide a motor driven wheel chair comprising two spaced apart wheels having a frame supported by said wheels and positioned between said wheels below the axis 40 of said wheels and having a chair positioned between the wheels and supported from the frame, said frame having small caster wheels at the front and rear portion thereof to engage with the floor on which the chair rests and prevent tipping.

45 Other and more specific objects of the invention will be apparent from the following description taken in connection with the accompanying drawings.

50 In the drawings

Fig. 1 is a view partly in side elevation and partly in vertical section of a motor driven wheel chair constructed in accordance with this invention.

55 Fig. 2 is a view partly in plan and partly in

horizontal section substantially on broken line 2—2 of Fig. 1, of my motor driven wheel chair.

Fig. 3 is a fragmentary plan view of a portion of a chair arm showing electric switch mechanism connected therewith.

Fig. 4 is a wiring diagram showing diagrammatically the electrical devices and connections therefor.

Fig. 5 is a fragmentary plan view showing a modified form of driving means.

Like reference numerals designate like parts throughout the several views.

In the drawings, 10 designates a frame capable of supporting the electric driving means required for operating the chair. Preferably this frame 15 10 consists of a platform having transverse members 11, on the top side thereof and having cover means 12 on the transverse members 11. Two wheel supporting brackets 13 are secured to the frame 10 near opposite sides thereof and extend 20 upwardly therefrom. Two wheels 14 are journaled on the wheel supporting brackets 13.

Two chair supports 15 of inverted U shape extend upwardly from the frame 5, adjacent the sides thereof and a chair 16 is adjustably 25 mounted on the chair supports 15 by bracket means 17. A screw 18 in the bracket means 17 may be loosened to permit adjustment of the chair on the chair supports 15 and tightened to hold the bracket means 17 immovable on the 30 chair supports 15.

Two drive shaft assemblies designated generally by 19 and 20 in Figs. 1 and 2, are provided on the frame 10 and extend crosswise of said frame in front of and to the rear of the wheels 14 35 respectively. These two drive shaft assemblies are of duplicate construction and the following description and numerals apply equally well to either one. Each drive shaft assembly comprises a tubular shaft or quill 21 journaled in bearings 40 22 that are secured to the frame 10. Two clutch members 23 on the respective ends of the tubular shaft 21, engage with the bearings 22 and prevent endwise movement of the tubular shaft 21.

Two drive shafts 24 and 25 are telescopically 45 and rotatably disposed within the tubular shaft 21 and project outwardly from the ends thereof. A bearing member 26 is provided for each drive shaft. A collar 27 is secured to each drive shaft 24 and 25 adjacent the bearing member 26 to 50 prevent outward movement of the shaft. A clutch member 28 is provided on each shaft 24 and 25 between the collar 27 and the clutch member 23 on the adjacent end of the tubular shaft 21.

Each pair of clutch members 23 and 55

28 have complementary teeth 29 and grooves 30 adapted to interfit in the manner common to clutches. Each clutch member 28 is connected with its shaft by a spline or key member 31 so that the clutch member 28 and its shaft must rotate together but the clutch member is left free to move longitudinally of the shaft. A gear pinion 32 on the outer end portion of each shaft meshes with a gearwheel 33 on the adjacent wheel 14. A sprocket wheel 34 is secured to each tubular shaft 21 and link belts 35 and 36 connect the respective sprocket wheels 34 with two sprocket wheels 37 and 38 of a speed reduction gear 39. The two sprocket wheels 37 and 38 rotate in opposite directions so as to drive the two tubular shafts 21 in opposite directions. An electric motor 40 is connected by belt means 41 with the speed reduction gear 39 for driving the same.

20 Each clutch member 28 has a shifter arm 42 connected therewith. Each shifter arm 42 is fulcrumed on a pivot 43 and has a spring 44 connected with it in such a manner as to urge the clutch 28 into a disengaged position. Preferably 25 a stop member 45 is provided for limiting the movement of the clutch arm in one direction. Four electromagnets 46, 47, 48 and 49 are provided for operating the four clutches. These electromagnets are shown in plan in Fig. 2, and 30 are shown diagrammatically in Fig. 4. Each electromagnet is positioned so as to exert a pull on an armature 45' on the adjacent lever 42.

A caster wheel 9 is provided at each corner of the frame to stabilize and balance the chair 35 and to provide for easy turning of said chair in all directions. The caster wheels are positioned so that they are slightly above the floor when the frame 10 is parallel with the floor. This allows for a slight tilting movement of the 40 frame, prevents more than one pair of said caster wheels from contacting the floor at one time, facilitates going over door sills, rugs, and like obstructions and insures that the major portion of the weight of the chair will always be carried by the main wheels 14.

45 Preferably the motor 40 is a direct current motor and is electrically connected in series with two six volt batteries 50 and 51, as diagrammatically shown in Fig. 4. In said Fig. 4, 50 the two batteries 50 and 51 are connected with each other by a conductor 52 and said batteries are connected with the motor 40 by conductor 53, conductor 54, relay operated switch 55 and conductors 56 and 57. The relay 58 that operates switch 55 is connected by conductors 59 and 57 with one side of one of the batteries, such as the battery 51, and by conductor 60, switch 61 and conductors 62, 63 and 52 with the other side of the battery 51. This provides 60 for energizing the relay 58 with six volt current when the switch 61 is closed. Four switches 64, 65, 66 and 67 control the flow of current to the respective electromagnets 46, 47, 48 and 49 by which the clutch members 28 are operated.

65 Preferably the electromagnets are adapted to be energized with six volt current. To this end the two electromagnets 46 and 48 on one side of the chair are preferably connected with one battery, such as the battery 51 and the two electromagnets 47, and 49 on the other side of the chair are connected with the other battery 50. This approximately equalizes the load on the two batteries. The electromagnet 46 is connected by conductors 68, 62, 63 and 52 with one 70 side of battery 51 and by conductor 69, switch 75

64 and conductors 70 and 57 with the other side of battery 51. The electromagnet 48 is connected by conductor 71 with one side of battery 51 and by conductor 72, switch 66 and conductors 73 and 51 with the other side of battery 51. 5 The electromagnet 47 is connected by conductors 74 and 53 with one side of the battery 50 and by conductor 75, switch 65, and conductors 76 and 63 with the other side of the battery 50. The electromagnet 49 is connected by conductors 77 10 and 53 with one side of the battery 50 and by conductor 78, switch 67 and conductors 79, 76 and 63 with the other side of the battery 50. Obviously, with the connections just described, the switches 64, 65, 66 and 67 control the electromagnets 46, 47, 48 and 49 respectively. The switch 61 controls the relay 58 which in turn controls the circuit to the motor 40.

Preferably the switches 61, 64, 65, 66 and 67 are positioned in or on an arm 80 of the chair, 20 as shown in Figs. 1 and 3 so that they are easily accessible to the operator. These switches are preferably of the push button type as shown. A flat plate 81 is preferably connected by pivot means 82 with the chair arm 80 and positioned 25 to engage the switch 61 and form a comfortable rest upon which the wrist of the operator may be placed when the switch is to be operated. A spring 83 urges the switch 61 into open switch position and said spring is preferably strong 30 enough so that the weight of the hand and forearm of the operator will not close the switch 61 unless a conscious effort is made to close said switch 61 by exerting a downward pressure on the plate 81. If the switch 61 should be closed 35 accidentally it will start the motor 40 but this will not move the chair unless one or more of the switches 64, 65, 66 and 67 are closed at the same time as the switch 61.

Means is provided to prevent the two switches 40 64 and 66 from being closed at the same time and to prevent the two switches 65 and 67 from being closed at the same time. The means for accomplishing this purpose shown in Figs. 1 and 3 consists of a lever plate 84 overlapping each pair 45 of switch buttons 64—66 and 65—67 and pivoted between the two switch buttons for rocking movement. When one end of a lever plate is pressed inwardly the opposite end thereof will move outwardly and prevent pressure on the other switch button of the pair. Other means of well known form may be provided for preventing the closing of one switch when the other switch of the pair is closed. Obviously the switch means may be separate from the arm of the chair and may be positioned for operation by the feet or by any other part of the body, depending on the physical condition of the patient using the chair. 55

In the operation of this device, whenever the switch 61 is closed the motor 40 will be operated but the chair will not be moved unless one or more of the other switches 64, 65, 66 or 67 is closed at the same time. If the operator desires to move forward he will close switches 61, 66 and 67. This will operate motor 40 to drive the tubular shafts 21 and at the same time energize electromagnets 48 and 49 to engage the two clutches on the forward shaft assembly and drive the wheels 14 in the proper direction to move 70 the chair forward. By simultaneously closing switches 61, 64, and 66 the electromagnets 46 and 47 will be energized and the clutches of the rear shaft assembly engaged to drive the wheels in the proper direction to move the chair rear- 75

wardly. If the switch 61 and any one of the switches 64, 65, 66 or 67 are simultaneously closed one wheel 14 will be driven and the opposite wheel 14 will stand still and the chair will be turned on the vertical axis of the non-driven wheel. If the switch 61 and two diagonally opposite switches, such as the two switches 64 and 67 or the two switches 66 and 65 are simultaneously closed then one wheel 14 will be rotated 5 in one direction and the other wheel will be rotated in the opposite direction and the chair will be turned substantially on its own vertical axis and in the least space in which it is possible to turn said chair. This gives to any 10 operator that is able to operate the switches complete control of the chair and makes it possible for them to maneuver the chair in the least possible space.

In Fig. 5, I have shown a modified form of drive 20 means comprising a sprocket wheel 87 on each drive shaft 24 and 25 connected by a link belt 88 with a sprocket wheel 89 that is secured to the adjacent wheel 14. This provides two link belt driving connections to each wheel 14.

The foregoing description and accompanying 25 drawings clearly disclose a preferred embodiment of my invention but it will be understood that this disclosure is merely illustrative and that changes may be made within the scope and spirit 30 of the following claims.

I claim:

1. A motor driven wheel chair comprising two spaced apart wheels, a frame supported by said wheels and positioned between said wheels below the axes of said wheels; a chair supported from said frame and positioned between said wheels; two drive shafts positioned in front of said wheels; two other drive shafts positioned to the rear of said wheels; a driving connection between each drive shaft and a wheel; driving means for said drive shafts; and an independent control for selectively connecting each drive shaft with said driving means, whereby either of said wheels may be driven in either desired direction.
2. A motor driven wheel chair comprising two spaced apart wheels, a frame supported by said wheels and positioned between said wheels below the axes of said wheels; a chair supported from said frame and positioned between said wheels; two driven members positioned transversely of

said frame adjacent the front and rear portions of said wheels respectively; two shafts aligned with each driven member and extending in opposite directions therefrom; clutch means releasably connecting each shaft with one of said driven members; a driving connection between each shaft and an adjacent wheel; driving means connected with said driven members and control means connected with each clutch for selectively driving or stopping any desired shaft. 10

3. A motor driven wheel chair comprising two spaced apart wheels, a frame supported by said wheels and positioned between said wheels below the axes of said wheels; a chair supported from said frame and positioned between said wheels; two driven members positioned transversely of said frame adjacent the front and rear portions of said wheels respectively; two shafts aligned with each driven member and extending in opposite directions therefrom; clutch means releasably connecting each shaft with one of said driven members; a driving connection between each shaft and an adjacent wheel; driving means connected with said driven members; an electromagnet controlling the operation of each clutch; 25 and switch means operable by the occupant of the chair for selectively energizing any of said electromagnets to thereby engage any desired clutch.

4. A motor driven wheel chair comprising two spaced apart wheels, a frame supported by said wheels and positioned between said wheels below the axes of said wheels; a chair supported from said frame and positioned between said wheels; two rotatably mounted tubular shafts positioned 35 transversely of said frame adjacent the front and rear portions of said wheels; two driving shafts rotatable within each tubular shaft and extending outwardly from the respective ends of the tubular shaft; a clutch for selectively connecting 40 or disconnecting each driving shaft relative to its respective tubular shaft; an electromagnet operatively connected with each clutch; switch means operable by the occupant of the chair for selectively energizing any of said electromagnets; 45 means for driving each of said tubular shafts; and driving means connecting each driving shaft with the wheel adjacent thereto.

HOMER P. SMITH. 50
